UNITED STATES PATENT OFFICE.

ALFRED WILLIAM BENNIS, OF BOLTON, ENGLAND.

INTERNAL-COMBUSTION ENGINE.

1,363,708.

Specification of Letters Patent. Patented Dec. 28, 1920.

Application filed June 4, 1918. Serial No. 238,227.

To all whom it may concern:

Be it known that I, ALFRED WILLIAM BENNIS, subject of the King of Great Britain, residing at Bolton, in the county of 5 Lancaster and Kingdom of England, have invented certain new and useful Improvements in and Relating to Internal-Combustion Engines, of which the following is a specification.

10 This invention relates to improvements in internal combustion engines with the object of more effectively cooling the engine and certain of its working parts by an internal circulation of air or gas.

15 According to the present invention a reciprocating part of an internal combustion engine such as a piston, or valve is chambered or hollow and is cooled by an air or gas stream passed to and from it through 20 ports in the guiding parts for said piston, valve or the like, which ports are in periodic or continuous communication with said chambered or hollow portions.

The invention is more particularly described with reference to the accompanying drawings in which several applications of the invention are shown by way of example.

In the drawings:—

25 Figure 1 is a plan sectional view through a piston and cylinder on the line A B of Fig. 3.

Fig. 2 is a similar view taken lower down the cylinder on the line C D of Fig. 3.

30 Fig. 3 is a sectional front elevation of a piston and cylinder of an internal combustion engine.

Fig. 4 is a similar sectional side elevation.

Fig. 5 is a partial outside view.

35 Fig. 6 is a sectional elevation of a modification.

Referring to Figs. 2 to 6 of the drawings, a cylinder 14 is provided with longitudinal cooling ribs 15, but it can have radial ribs or a water jacket or other external cooling 40 arrangement if desired.

A piston 16, is carried on a gudgeon pin 17 on a connecting rod 18 on the crank 19 of usual form.

In one form the piston is of lantern shape 50 having a top annulus 20 provided with piston rings 21 and a lower annulus 22 provided with a bearing or scraper ring 23. Between these two parts bearing against the walls of the cylinder a chamber 25 is formed.

This chamber may be divided longitudinally 55 by axial fins 26 on the piston, or these may be circumferential to the piston or spiral.

The underneath part of the head 27 of the piston can be provided with heat radiating or alternatively air or gas stream guiding 60 fins 28.

The fins 26 and 28 may form intercommunicating chambers arranged in series to one another or if desired several such chambers may be arranged connected in parallel 65 to one another.

Air for cooling purposes, or mixture from a carburetor as set forth above, may pass into the chambers formed by the fins 26, through ports 29 in the walls of the cylinder 70 14. In certain cases the chambers may be so arranged that air may pass into the cylinder through ports 29 up and across the piston and down the other side, thence out through ports 30. 75

The bearings 31 for the gudgeon pin 17 may be stiffened or reinforced by a rib or ribs 32, carried up to the pinion head 27 and the gudgeon pin 17, may be hollow so that air may pass through it from the chambers on one side of the piston to the chambers on the other side to cool the same. As the gudgeon pin may project slightly into the chambers on the side of the piston as shown at 33, this will conveniently allow for 85 means for securing the gudgeon being applied to it on the outside if desired.

If desired on the sides of the piston at right angles to the axis of the gudgeon pin the ribs or fins 26 may be spaced nearer together to provide a bearing surface against the cylinder walls. The fins 26 may all around the piston be substantially in contact with the cylinder walls if desired. 90

It is obvious that either the passage or port 95 leading the air in or out may be a short one in which case to maintain continuous connection with the outside the port or passage in the piston, valve or the like port must be substantially equal in length to the stroke 100 of the port, or alternatively the passage or port in the guiding part must be of this latter length to give constant communication with a short port on the moving part. In certain cases both port on the fixed part and 105 passage on the moving part may be long.

Again in certain cases it may be desirable to connect the moving part with the port in

the guiding part at certain times only in the stroke of the part, in which case both port and passage will be short.

In certain cases hollow chambers within 5 the piston may communicate with the hollow spaces formed between piston and cylinder.

The arrangement may also be applied to sleeve valve engines as shown in Fig. 6 in 10 which inlet and exhaust slots 80, 81 are arranged through the valve 82 to provide continuous communication with the ports 83 and 84 on the cylinder and the air passages 85 in or on the piston 86 or again the inner 15 sleeve valve 87 itself may be arranged as a hollow air or gas passage carrying member, similar in construction to the piston except as to the hollow head whereby the longitudinal or spiral or other passages may in turn 20 be swept by the stream of air or gas and continuously pass through the ports or slots and through the piston, so cooling both sleeve valve and piston.

In rotary engines where the cylinders revolve around a crank shaft or the like, a 25 cowl may be provided to such cylinders and ducts or pipes from such cowls to cylinder and valve stem ports in order to cause a current of air to pass through such ports.

Again the air may be forced or aspirated 30 through a hollow crank shaft, connecting rods, gudgeon pin, thence by ducts through the gudgeon pin bearings to the hollow piston head whence it may escape through the 35 piston skirt passages and cylinder ports.

Where the engine is operating with a closed crank case air could, for instance, be

forced by the downward motion of the piston through a suitable passage into the said piston, across it and then into the atmosphere 40 or preferably into the carbureter as normal air supply for the engine, or again around the carbureter as a heating means for this.

I declare that what I claim is:—

1. As an article of manufacture a piston 45 comprising a body, ribs along said body parallel with its axis, ribs across the top of said body forming a passage uniting the axial spaces on one side with those on the other, a piston ring at the top of said body 50 bounding the space at the end of the axial ribs and a piston ring at the bottom of the body bounding the space.

2. As an article of manufacture a piston comprising a body, radial ribs along said 55 body parallel with its axis, ribs parallel to one another across the top of said body, a piston ring at the top of said piston bounding the space at the end of the said radial axial ribs, and a piston ring at the bottom of the 60 body bounding said space.

3. As an article of manufacture a piston for an internal combustion engine having castellated sides between its upper and lower rings and a hollow passage between the castellations on one side and those on the opposite side. 65

In witness whereof, I have hereunto signed my name this 14th day of May, 1918, in the presence of two subscribing witnesses.

ALFRED WILLIAM BENNIS.
